UNITED STATES PATENT OFFICE.

ROBERT KLINE, OF CLEVELAND, OHIO.

FEEDING DEVICE FOR WRINGERS.

Application filed April 7, 1922. Serial No. 550,511.

To all whom it may concern:

Be it known that I, ROBERT KLINE, a citizen of the United States, and a resident of Cleveland, county of Cuyahoga, State of Ohio, have invented certain new and useful Improvements in Feeding Devices for Wringers, of which the following is a specification.

This invention relates to power clothes wringers and more particularly to feeding devices therefor. One of the objects of the invention is to provide a feeding device for the clothes that may be readily attached to existing wringers or incorporated in the design of wringers of the type now commonly in use.

A further object of the invention is to provide a feeding device that will be of simple construction and comparatively inexpensive to manufacture.

A further object of the invention is to provide a feeding device that will be convenient to operate and adapted to permit feeding the clothes into the rolls at any point in their length without any necessity for the operator to get her fingers so close to the rolls that there is danger of their being drawn in.

Other objects of the invention and the features of novelty will be apparent from the following description taken in connection with the accompanying drawings, in which:

Figure 1 is a side elevation of a feeding device embodying my invention, shown in relation to wringer;

Fig. 2 is a rear elevation of the feeding device shown in Fig. 1.

Fig. 3 is a top plan of the same;

Fig. 4 is a bottom plan; and

Fig. 5 is a central longitudinal section at right angles to the wringer rolls;

Fig. 6 is a fragmentary section on the line 6-6 of Fig. 5.

The form of the invention illustrated in the drawings is for attachment to existing wringers and in Fig. 1 the method of attachment and the position of the device is shown, the wringer rolls being indicated in broken lines at A and the front cross board of the wringer at B. The feeding device comprises a frame or support D having the pairs of cooperating lugs D', at its opposite ends to fit over the board B, one of the lugs of each of these pairs carrying a clamping screw E by which the frame is secured to the

board B. The frame D carries on its upper side a slidable feed plate C. The front edge of the plate C has a depending flange in the middle of which there is formed a depression F to receive the finger of the operator so as to facilitate movement of the plate. The corners F' are rounded so as to permit the clothes to be drawn over them without catching buttons or otherwise injuring them. Projecting rearwardly from said flange and secured at the center thereof is a rod G by which the plate C is connected with the frame D and guided in its movements thereon. The rod G extends through a bearing H depending from the frame D, the opening in this bearing being preferably tapered, as indicated in Fig. 5, to provide a loose fit for the guide rod G and permit practically a universal movement therein.

Lugs J project downward from the underside of the plate C, into an opening or openings K in the frame D, and serve to limit the movements of the plate C, to and from the wringer rolls, by engagement with the opposite sides of these openings, as will be readily seen from Fig. 4. The spring I, coiled around the rod G, exerts a pressure on the plate C so as to retract the plate from the wringer rolls when the operator releases the plate.

In order to make the plate C more easily movable on the frame D, I have provided rollers N, at the opposite ends of the frame, which engage with the underside of the plate C. On the end of the rod G, I have mounted the rollers L which are adapted to engage with the lower surface of a bridge M in the central part of the frame D (see Fig. 5).

In the operation of the device the clothes are placed on the plate C so as to overhang the rear edge of the plate and hang down from the front edge. The operator then moves the plate toward the wringer rolls and the latter catching the clothes draw them through in the usual manner, the operator in the meantime, having released the plate and the spring I having retracted it to its initial position. In the operation of wringers the large pieces are usually put in at the middle of the rolls and frequently take up their full length but smaller pieces may be inserted at either end and my feeding device is especially adapted for feeding

pieces into either end of the rolls. In this case the pieces are laid on the sides of the plate C and first one side and then the other may be moved toward the wringer rolls. 5 This results in a sort of swinging or oscillating movement of the plate as the construction permits either end to be moved toward the rolls independently of the other, due to the tapered opening in the bearing H 10 permitting a practically universal movement of the rod G therein. In these swinging movements of the plate C it will swing about one or the other of the lugs J because the spring I will maintain one of these lugs 15 against the side of the opening K in the frame D when the opposite end of the plate is moved toward the wringer rolls.

In case the clothes become wrapped around the lower wringer roll A, as sometimes happens, they will engage with the underside of the plate C and tilt the latter, the rollers L contacting with the undersurface of the bridge M and thus permitting the plate C to be retracted by the spring I. 25 Normally the rollers L are out of contact with the bridge M, as is indicated in Fig. 5.

While I have illustrated and described one form of my invention it will be understood that changes may be made in the details without departing from the spirit of the invention which is defined in the appended claims.

Having thus described my invention, what I claim is:

- 35 1. In a safety feed device for a pair of wringer rolls, a support mounted in front of said rolls, an inclined plate movable on said support, a guide member on and parallel with said plate, a bearing therefor in said support, a return spring upon said guide member and a roller upon the inner end of said guide member and a bearing member for said roller, substantially as described.
- 40 2. The combination with the rigid frame and rollers of a clothes wringer, of a bracket secured to said frame and having an inclined upper surface, a feed plate slidably movable upon said inclined upper surface 45 of said bracket, said bracket provided with a longitudinal opening in its upper face, the longitudinal sides of said opening forming stop members, spaced lugs upon the lower surface of said sliding plate extending into said opening, rollers on said bracket on which said plate travels, a central guide rod secured to said plate underneath the same, said rod having a bearing in said bracket, an inclined bearing surface on the lower face of said bracket and rollers on said rod adapted to engage with said inclined surface when the upper edge of the plate is raised by the action of clothes in the wringer.
- 50 3. In a wringer, a bracket having an in-

clined upper surface and provided with an opening in the said upper surface, a plate slideable on said bracket and provided with spaced lugs entering said opening, the front and rear sides of said opening serving alternately as stops for said plate, a central guide rod on said plate, a bearing therefor in said bracket, an inclined surface on the lower side of said bracket, rollers on said guide rod normally out of engagement with said inclined lower surface of said bracket, a return spring on said guide rod and rollers on said bracket engaging spaced positions on said plate.

4. In a wringer, a bracket provided with an opening in the upper surface, a plate slideable on said bracket and provided with spaced lugs entering said opening, the front and rear sides of said opening serving alternately as stops for said plate, a guide rod in said plate, a bearing therefor in said bracket, an inclined surface on the lower side of said bracket, rollers on said guide rod normally out of engagement with said inclined lower surface of said bracket, a return spring on said rod, the front edge of said plate provided with a depression engageable by the finger of the operator.

5. A guard for a wringer including a bracket having a central guide and provided with means for securing it in position on a wringer, a slideable plate resting upon and supported by the bracket, and a guide rod extending from the front portion of the slideable plate and passing through the central guide and slidably connecting the plate with the same and having means to permit a swinging movement, and means for limiting the movement of the plate.

6. A feeding device for a wringer including a support to be rigidly attached to the wringer, a slideable plate on said support, a guide rod and a bearing therefor one of which is carried on the under side of said plate and the other of which is on said support, said bearing having an opening shaped to permit lateral swinging movement of said plate, and spring means for retracting said plate from the wringer rolls.

7. A feeding device for a wringer including a support to be rigidly attached to the wringer, a slideable plate on said support, a guide rod carried by said plate centrally upon the under side thereof, a bearing on said support for said guide rod having an opening shaped to permit lateral swinging movement of the plate so that either end of said plate may be advanced toward the wringer rolls independently of the other end, cooperating stops on said support and plate to limit the movements of the plate, and spring means for retracting said plate from the wringer rolls.

8. The combination with a clothes wringer, of a fixed guiding board directed toward

the space between the wringer rolls, a feeding board movable over said fixed board toward and from the rolls, the upper face of said feeding board being unobstructed and adapted to have clothing laid thereon, and

vanced and shove the same into the space between said rolls, and yielding means adapted to automatically withdraw said feeding board from said rolls when released. 10

In testimony whereof I affix my signature.

ROBERT KLINE.
